FUEL SAVING DEVICE

Roy C. Lee, Irvington, N. J.

Application August 3, 1934, Serial No. 738,357

6 Claims. (Cl. 261—78)

This invention relates to a fuel saving device which may be termed a carburetor and one object of this device is to provide a device of this character which is so constructed that a mixture of air and liquid fuel such as gasoline may be injected into a mixing chamber of a casing adapted to be attached to the fuel intake of an internal combustion engine and the fuel thoroughly mixed in the chamber with air drawn into the same by suction during operation of the engine to create a good combustible mixture.

Another object of the invention is to provide a device of this character wherein the air and charge of vaporized fuel will be drawn into the mixing chamber in proper proportion according to the speed at which the engine is running, this being accomplished due to the fact that the air and vaporized fuel are drawn into the chamber by suction exerted by the engine.

Still another object of the invention is to provide the device with an injector shiftable towards and away from an inlet nipple of the casing whereby the proper suction will be exerted through the injector and the proper quantity of vaporized fuel injected into the casing.

A still further object of the invention is to provide improved means for supplying liquid fuel to the injector and prevent an excessive quantity being drawn into the injector due to an excess quantity of gasoline in the gasoline container of the device.

Another object of the invention is to produce a device of this character which is simple in construction, easy to adjust and not liable to get out of order.

With these and numerous other objects in view, my invention consists in the novel features of construction, combination and arrangement of parts as will be hereinafter referred to and more particularly pointed out in the specification and claims.

In the accompanying drawing forming a part of this application:

Figure 1 is a section taken longitudinally through the improved carburetor;

Figure 2 is a section taken transversely through the air inlet of the mixing casing taken along the line 2—2 of Figure 1; and

Figure 3 is a top plan view of the injector forming part of the carburetor.

In describing the invention, I shall refer to the drawing in which similar reference characters designate corresponding parts throughout the several views. The casing 1 which defines a mixing chamber 2 is cylindrical in shape and

at its open inner end is provided with a flange 3 having bolt receiving openings 4 formed therein in order that the casing may be connected to the intake manifold of an internal combustion engine. At its outer end the casing is formed with a head 5 through which extends a nipple 6 carrying a securing nut 7 upon its outer portion and intermediate its length the casing is provided with a side arm 8 constituting an air inlet. The outer end portion of this arm is extended outwardly as shown in Figure 2 to form a mouth 9 in which is fitted a ring which is held in place by a set screw 11 shown in Figure 1. The ring constitutes a valve seat and it will be noted that the ring has a frusto-conical outer face 15 which converges inwardly to concentrate air as it is drawn inwardly through the arm. A cross bar 12 extends diametrically across the ring 10 and through this bar extends a valve stem 13 having at its inner end a concavo-convexed valve head 14 normally held against the inner end of the valve seat by a spring 15 coiled about the stem between the cross bar and an abutment 16 carried by the outer end portion of the stem. An adjusting nut 17 is also carried by the stem to engage the abutment and regulate tension of the spring. By this arrangement, the suction necessary to open the valve can be controlled and the quantity of air drawn into the mixing chamber during operation of the engine regulated.

Vaporized liquid fuel such as gasoline is to be fed into the mixing chamber during operation of the engine and in order to do so there has been provided an injector 18 having an enlarged base 19 which rests upon a bracket extending longitudinally from the outer end of the casing 1 below the nipple 6. At its inner end the bracket is bent upwardly to form an attaching portion or tongue 21 formed with an opening through which the nipple passes and this tongue is engaged between the nut 7 and end of the casing so that when the nut is tightened the bracket will be firmly secured in a horizontal position and the nipple also secured in place.

A spring 22 urges the injector away from the casing and in order to adjust the injector towards the casing there has been provided a rod 23 extending longitudinally of the bracket through the base 19 and carrying an adjusting element 24 which when rotated will cause the injector to move longitudinally upon the bracket, after the injector has been shifted along the bracket or track to a desired position and the lock nut 25 tightened, the injector will be firmly held in a set position with its inner discharge end spaced

outwardly from the nipple or extended into the nipple a desired distance according to the suction which it is desired to have created through the bore 26 of the injector. The bore is enlarged in spaced relation to the discharge end thereof to form a chamber 27 having side openings 28 constituting air inlets and in order to control flow of air through the injector there has been provided a needle valve 29. This needle valve is movable towards and away from a closed position by grasping its turning knob 30 and rotating the valve and as the knob is engaged by the free end of a spring strip 31 carried by the casing of the injector the valve will be held in an adjusted position.

Liquid fuel is supplied to the injector through a tube or pipe 32 extending downwardly therefrom through a slot formed in the bracket and below the bracket the tube carries a socket 33 to receive the upper end of the neck 34 which projects upwardly from the cap or cover 35 of a container 36 formed of glass, metal or any other desired material. The tube 32 extends down into the container quite a distance and has its lower portion engaged through a float 37 carrying a depending yoke 38. This yoke at its lower end is connected to the stem of a valve 39 which slides through the inlet neck carried by the bottom 40 of the container and as the valve moves vertically with the float it will be moved into and out of a closed position according to movement of the float. Fuel is fed into the container through a pipe 41 connected with the inlet neck and it will be readily seen that as the container is filled the valve will be gradually moved upwardly until it is finally closed. Therefore, too much gasoline can not accumulate in the container and also if an automobile is traveling over a rough road jolting can not cause flooding as the valve will close as the gasoline surges upwardly in the container and effectively prevent too much entering the container.

When this improved carburetor is in use, the flange 3 is attached to the intake of an internal combustion engine and the inlet neck of the container connected with a pipe leading from the fuel tank. The injector is adjusted to approximately the proper position upon the bracket and the butterfly valve 42 opened as far as desired. When the engine is turned over, suction will be created through the casing 1 and air drawn in through the side arm 8 while at the same time air will be drawn through the nipple and create a suction through the bore of the injector. The air sucked through the injector creates a partial vacuum in the tube 32 and gasoline will be drawn upwardly through this tube to mix with the air drawn through the injector and form a vaporous mixture which will be discharged as a jet from the injector through the nipple into the chamber 2. This vaporized fuel will mix with air drawn into the chamber through the side arm 8 and discharged into the intake manifold of the engine as a combustible mixture. The amount of suction will be controlled by the speed at which the engine is running and consequently the quantity of fuel will be automatically regulated. Shifting of the injector towards or away from the nipple will control suction exerted through the injector and therefore a lean or rich mixture can be provided as necessary. As the vapor delivered from the injector to the nipple 6 passes through space between the injector and the outer end of the nipple, it can be seen by an attendant who can

thus determine whether the vapor is feeding properly and in the desired quantity. Flow of fuel into the container will be controlled by the float actuated valve 39 and therefore the container will at all times be filled with the proper quantity of fuel and can not become flooded.

From the foregoing description of the construction of my improved device, the operation thereof and the method of applying the same to use will be readily understood. It will be seen that I have provided a simple, inexpensive and efficient means for carrying out the objects of the invention and while I have particularly described the elements best adapted to perform the functions set forth, it is obvious that various changes in form, proportion and in the minor details of construction may be resorted to, without departing from the spirit or sacrificing any of the principles of the invention.

Having thus described the invention what is claimed is:

1. A device of the character described comprising a casing having a fuel inlet at its outer end and an air inlet arm intermediate its length open at its outer end, a ring in the arm constituting a valve seat and having an inwardly directed frusto-conical outer surface, a bar carried by and extending diametrically across said ring at the outer end thereof, a concavo-convexed valve head in said arm inwardly of the ring and having its convexed face presented outwardly and slidably engaged, a stem for said valve head extending outwardly through said bar, a spring urging said stem outwardly to yieldably hold the valve head seated against the inner end of said ring, and means for injecting fuel into said casing through the inlet thereof comprising an injector facing the outer end of said casing in axial alignment with said fuel inlet and a fuel container communicating with said injector.

2. A device of the character described comprising a casing having a fuel inlet nipple projecting outwardly from its outer end and having its inner end adapted for connection with the intake of an engine, a bracket extending longitudinally from the outer end of said casing and having an upwardly extending attaching arm at its inner end bearing against the outer end of said casing about said nipple, a securing nut upon said nipple engaging the attaching arm to clamp the bracket against the casing when tightened, an injector slidably carried by said bracket and shiftable along the same towards and away from the outer end of the nipple, means yieldably resisting movement of the injector towards the nipple, and a fuel container communicating with said injector.

3. A device of the character described comprising a casing having a fuel inlet at its outer end and having its inner end adapted for connection with the intake of an engine, an air inlet being provided intermediate the length of the casing, a bracket extending longitudinally from the outer end of said casing, an injector supported upon said bracket in axial alignment with said fuel inlet, a rod extending longitudinally of said bracket and engaged through said injector, a spring urging said injector towards the outer end of said bracket, an adjusting element threaded upon said rod and engaging said injector to shift the injector towards said fuel inlet in opposition to the action of said spring and hold the injector in an adjusted position, and a fuel container communicating with said injector.

4. A device of the character described comprising a casing having a fuel inlet at its outer end

2,029,110

and having its inner end adapted for connection with the intake of an engine, an air inlet being provided intermediate the length of the casing, a bracket extending longitudinally from the outer end of said casing, an injector supported upon said bracket in axial alinement with said fuel inlet, and shiftable along the bracket towards and away from the fuel inlet, a tube extending downwardly from said injector through said bracket, a fuel container secured about said tube and having an inlet in its bottom, an inwardly opening valve for the inlet of the container, and a float in said container having a yoke extending downwardly therefrom and engaged with the valve for moving the valve upwardly to a closed position.

5. A device of the character described comprising a casing having its inner end adapted for connection with the intake of an engine and having a fuel inlet at its outer end, an air inlet arm extending from said casing, an inwardly opening valve for said arm yieldably held closed, a manually operated valve in said casing between the arm and inner end of the casing, an injector facing the outer end of said casing and adjustable 20 towards and away from the fuel inlet thereof, a

fuel container, a tube leading from the upper end of said container into said injector, a fuel inlet neck at the bottom of the container, a valve movable into and out of position for closing the fuel inlet neck, and a float in said container connected 5 with the valve of the neck for closing the valve when fuel in the container raises the float above a predetermined position.

6. A device of the character described comprising a casing having a fuel inlet at its outer end 10 and having its inner end adapted for connection with the intake of an engine, a track from the outer end of said casing longitudinally thereof and provided with an opening intermediate its length, an injector slidable along said track to- 15 wards and away from the inlet of the casing, a fuel container below said track having a discharge tube extending through the opening in the track and connecting the container with the injector, resilient means yieldably resisting movement of the injector towards the fuel inlet, and adjustable means for limiting movement of the injector away from the fuel inlet.
